UNITED STATES PATENT OFFICE

CHARLES W. WILSON, OF RENTON, WASHINGTON

FAUCET

Application filed August 4, 1927, Serial No. 210,652. Renewed November 9, 1929.

This invention relates to an improvement in faucets and particularly to a valve operating means therefor in the use of which the valve is arranged as a quick-acting valve in both opening and closing, requires but the minimum amount of movement in the handle to open or close the valve, and utilizes the pressure of the water as a means for maintaining the valve on its seat.

- 10 The principal object of the present invention is to provide a valve structure for faucets or the like including a valve barrel in which the valve is mounted for cooperation with the ground seat under the action of a 15 spring combined with an operating rod barrel separable from and cooperating with the valve barrel in which operating rod barrel the rod is mounted for rotation and longitudinal movement under cooperating cam 20 parts on the rod and barrel, the rod in one movement forcing the valve from its seat and in the opposite movement permitting the valve to move to its seat under the influence of the spring.
- 25 A further object of the invention is the provision of the operating rod with a head serving as a valve in addition to the main valve with the parts arranged so that both valves open and close in unison to thereby 30 provide a double security against leakage.

A further object is the mounting of the operating rod barrel so that it may be removed at will from the faucet for repair or replacement, the main valve remaining closed 35 while the operating rod barrel is removed.

The invention is illustrated in the accompanying drawings, in which:

Figure 1 is a view in longitudinal section, partly in elevation, showing a faucet with 40 the improved valve and valve operating mechanism in position therein.

Figure 2 is an enlarged vertical section of the valve barrel and operating rod barrel in cooperative relation, the rod being omitted.

Figure 3 is a view in elevation of the rod.

Figure 4 is a broken sectional view of a faucet, partly in elevation, showing a modified mounting for the operating rod barrel.

Figure 5 is a section on line 5—5 of Figure 2.

Figure 6 is a view of the valve rod.

The invention is here illustrated as applied to a faucet comprising a body 1 having the usual inlet section 2 threaded at 3 for connection with the water system and having the usual outlet 4. The body has a central well 5 threaded at 6 throughout its length and formed at its lower end in line with the inlet 3 with an opening 7 to provide a water inlet to the well and oppositely and some distance above its lower end with an opening 8 constituting a water outlet from the well and communicating, of course, with the outlet 4 of the faucet.

A valve barrel 9 exteriorly threaded at 10 for cooperation with the threads 6 of the well is designed to be threaded into the well until its lower end is approximately on a line with the upper edge of the opening 7. This barrel, which is of cylindrical hollow form, has its lower end formed with a valve seat 11, preferably ground, and a correspondingly ground valve 12 is arranged to cooperate with said seat. A stem 13 having its upper portion reduced at 14 is integral with the valve, the upper reduced portion 14 being threaded to receive a U-shaped yoke 15 which is threaded onto the reduced portion to bear against the shoulder formed between the reduced portion and the portion 14.

The side arms 16 of the yoke have their upper ends turned laterally at 17 and extend substantially to the inner wall of the barrel, and a spring 18 is coiled about the yoke, bearing at its lower end on the bottom of the barrel and at its upper end beneath the lateral portions 17 of the yoke. Thus, the valve is influenced to a seating position by the spring 18. A coil spring 19 is arranged about the reduced portion 14 of the valve stem, its upper end being in coincidence with the upper surfaces of the lateral extensions 17 of the yoke.

An operating rod barrel 20 is arranged for threaded connection with the threads 6 of the well 5 above the valve barrel. This operating rod barrel has an upper portion 21 of less exterior diameter than the interior diameter of the well, an intermediate portion 22 which is exteriorly threaded for coopera-

tion with the threads 6 of the well, and a lower reduced portion 23 forming an annular chamber 24 with the wall of the well, and terminating in a lip 25 formed to cooperate at 5 26 with the upper edge of the valve barrel and interiorly shouldered at 27 to receive a gasket 28.

Formed on the inner surface of the operating rod barrel is an annular cam projection 29 formed with an inclined camway 30. The portion 23 of the operating rod barrel, which together with the well forms the chamber 24, is formed with a series of openings 31 to establish communication between 10 the interior of the operating rod barrel and the chamber 24, and, as will be noted from Figure 1 of the drawings, when the operating rod barrel is in place, the chamber 24 is in registry with the outlet opening 8 from the barrel, that is, with the outlet 4 of the faucet. 15

The operating rod 32 is formed at its lower end with a head 33 adapted to seat in the reduced portion 27 at the lower end of the operating rod barrel, the head being 20 formed to cooperate with the gasket 28, thus serving as a valve to seal the juncture when the head is in place therein. The rod 32 is formed with a cam projection 34 adapted to cooperate with the camway 30 in the barrel; 25 the formation of the camway 30 and cam projection 34 being such that on a comparatively slight turning movement of the operating rod, the cams cooperate to move the rod downwardly. It is to be particularly noted 30 that in the movement of the operating rod the head or valve 33 moves directly away from and toward the gasket 28; that is to say, there is substantially no rotative movement of the head 33 on the gasket. This insures 35 that the head cooperates with the gasket in the same position at all times, avoids undue wear of the gasket and thereby insures a more water-tight connection and increased life of the part.

40 The operating rod 32 is of a length to extend above the barrel and the upper end of the well 5 and to receive a closing cap 36 having a reduced projection 37 exteriorly threaded to cooperate with the threads 6 of the well, the cap having the usual sealing gasket 38 and being formed with an edge 39 to receive a wrench or the like, whereby the cap may be positioned or removed. The operating rod is formed at its upper end with 45 an angular projection 40 to removably receive an operating handle 41.

If preferred and as desired, the upper end 21 of the operating rod barrel may be flattened on opposite sides at 42 to permit the 50 use of an appropriate tool for seating and removing the operating rod barrel. The valve barrel 9, which is arranged for threaded cooperation with the bore of the faucet well, is designed to be initially applied in 55

proper position in the well and to remain in this position without removal.

In applying the parts, the valve barrel with the connected valve is screwed into the well until the valve is substantially on a line with the upper edge of the opening 7, any appropriate means being provided for limiting the downward movement of the valve barrel to this position. The operating rod barrel is then applied until its lower edge 70 25 is snugly seated on the formed edge 26 of the valve barrel, the operating rod being, of course, in position and turned so that its head 33 is seated against the gasket 28.

In this position, the valve 12 is seated 80 against the seat 11 and the flow of water is cut off, it being apparent that the pressure of the incoming water is acting freely against the body of the valve, tending to insure that it will remain on its seat in a non-leaking condition. The head 33 of the operating rod is, of course, of a diameter to fit within the valve barrel overlying, however, the upper surfaces of the lateral projections 17 of the yoke 15. When it is desired to open the 90 valve, a slight turning movement of the handle 41 causes the cam projection 34 on the operating rod to ride down the camway 30 in the operating rod barrel, with the effect to move the operating rod downwardly, causing the head 32 thereof to engage the lateral projections 17 of the yoke 15 and depress the valve 12. Water may now freely flow to the respective barrels, to and through the openings 31 in the operating rod barrel, into the 100 chamber 24 and so through the outlet 8 to the faucet outlet 4. The coil spring 19 serves to prevent chattering of the operating rod during operation of the parts.

105 It is to be particularly noted that the camway 30 is so formed that when the operating rod is depressed it will, in the final stages of its movement, be held in depressed position due to the cooperation of appropriate parts of the cam projection 34 and camway 30. When it is desired to close the valve, a slight 110 opposite turning movement of the handle places the parts under the influence of the spring 18, moving the valve rod 32 and valve 12 upwardly until the valve 12 seats and the head 33 of the operating rod seats against the gasket 28. The parts are thus in position to close the passage of water through the barrels and hence the water supply through the faucet is cut off.

115 Obviously, the operating rod barrel may be removed without disturbing the valve barrel and the latter acts as a closure against the flow of water notwithstanding the removal of the operating rod barrel as may be necessary for repair or replacement of parts.

An important feature of the valve, in addition to the double check, is the fact that the main valve 12 snaps to its seat on the turning of the operating rod, thereby insuring 120 130

an accurate positive closing wholly independent of any voluntary movement of the operator aside from the initial turning of the handle.

5 It will, of course, be apparent that the operating rod barrel, while preferably threaded into operative position as shown, need not necessarily be connected directly with the faucet. For example, as illustrated in Figure
10 4, the barrel may constitute an unthreaded member having a diameter to more or less snugly fit in the well, also unthreaded throughout its upper portion, this operating barrel being merely placed in position and
15 held in operative relation for the subsequent action of the parts by the closing cap 36.

What I claim to be new is:

A valve operating means for faucets, including a body having a vertical well therein
20 and formed with inlet and outlet openings to the well, the wall of said well being threaded, a valve barrel exteriorly threaded and adapted to be positioned in the well, a shoulder formed on the valve barrel providing a stop
25 for said barrel, a valve seat formed at the lower end of the valve barrel, a valve seating on said valve seat, a valve stem integral with the valve extending upwards into said barrel, said stem being reduced and threaded in its
30 upper portion, a U-shaped yoke carried on the valve stem, the reduced portion providing a shoulder upon which the bend of the yoke rests, the side arms of said yoke being bent laterally adjacent their extremities, a coil
35 spring bearing against the bottom of the valve barrel and the bent ends of the yoke, a second coil spring positioned over the reduced portion of the valve stem, a shoulder formed interiorly of the valve barrel above the yoke,
40 a gasket seated in said shoulder, a cam operating rod adapted for movement within the valve barrel and formed with a head adapted to seat on the gasket, said head also bearing against the second spring and bent yoke arm,
45 whereby movement of the operating rod unseats the head from the gasket, depresses the yoke which unseats the valve opening the inlet, the second spring preventing chattering of the operating rod.

50 In testimony whereof I affix my signature.
CHARLES W. WILSON.
